UNITED STATES PATENT OFFICE.

FRANCES N. WORKMAN, OF LOS ANGELES, CALIFORNIA.

UNDERGARMENT.

1,128,213.

Specification of Letters Patent.

Patented Feb. 9, 1915.

Application filed April 15, 1914. Serial No. 831,997.

To all whom it may concern:

Be it known that I, FRANCES N. WORKMAN, a citizen of the United States, residing at Los Angeles, in the county of Los Angeles, State of California, have invented new and useful Improvements in Undergarments, of which the following is a specification.

This invention relates to a lady's undergarment and particularly pertains to an undergarment combining a vest portion of woven fabric and a body portion of a knitted fabric.

It is the object of this invention to overcome the objectionable features of under-vests, union suits and the like formed wholly of knitted material, which objections reside in the fact that the knitted shoulder straps have a tendency to slip down on the arm, thus causing discomfort to the wearer, and also exposing the knitted fabric where sleeveless or thin sleeve waists are worn.

It is a further object to obviate the disagreeable features met in the use of the ordinary woven chemise, which is often substituted for the knitted garment to overcome the above mentioned objectionable features of the latter; the woven chemise, however, being objectionable in that it tends to gather in bunches beneath the corset by reason of its not conforming close to the body.

A further object is to provide an undergarment having an elastic knitted lower portion and a non-elastic woven upper vest portion, which will obviate the use of draw-strings and the like at the neck, and by which the use of a woven fabric will present a neat and dainty appearance when worn with thin waists or dresses.

The invention is illustrated in the accompanying drawing, in which: Figure 1 is a view illustrating the garment as applied. Fig. 2 is a detail illustrating a modified form of same. Figs. 3 and 4 are details showing the manner in which the non-elastic woven fabric is attached to the elastic knitted fabric; Fig. 4 showing the knitted fabric as expanded as when the woven fabric is stitched thereto, and Fig. 3 showing the knitted fabric as contracted and forming a fullness in the woven fabric.

More specifically, 5 indicates the knitted lower portion of the undergarment, which may comprise the body and leg portions of a union suit or the body portion of an undershirt; the upper edge 6 of this portion of the undergarment terminating at a point above the waist line or immediately below the breasts; this portion of the garment being formed of elastic knitted fabric conforms readily to the body so as not to gather and form bunches beneath the corset. Stitched to the upper edge 6 of the knitted portion 5 of the garment is a vest 7 formed of a non-elastic woven fabric, such as nain-sook, cambric, muslin or the like, which vest is preferably continuous around the bust and back, or may be opened down the front, as shown in Fig. 2, and provided with buttons 8 and button-holes 9.

The upper portion of the vest 6 is formed with shoulder straps 10 which complete the arm hole and neck portions of the garment, the edges of which may be suitably trimmed.

In connecting the non-elastic vest portion 7 to the elastic body portion 5, the edge 6 of the latter is expanded, as shown in Fig. 4, so that when the knitted fabric contracts to its normal shape a fullness 11 will be formed in the woven fabric at its point of intersection with the knitted fabric.

The important features of this invention resides in the fact that the elastic knitted fabric will conform closely to the body around the waist and beneath the breasts, the elastic knitted fabric acting, where the two fabrics are joined together, in a manner like that of a draw-string, and the non-elastic woven vest portion of the garment will supply the desired fullness over the breasts and will readily retain its position on the wearer by reason of its non-elasticity.

What I claim is:

1. A lady's undergarment, comprising a body portion formed of an elastic knitted fabric, and a vest portion formed of a non-elastic woven fabric affixed to the upper edge of the elastic fabric.

2. A lady's undergarment, comprising a body portion formed of an elastic knitted fabric, a vest portion formed of a non-elastic woven fabric affixed to the upper

edge of the elastic fabric, the point of junction between the knitted fabric and the woven fabric being arranged to extend immediately below the breasts of the wearer,
5 the woven fabric having a fullness at its juncture with the knitted fabric.

In witness that I claim the foregoing I

have hereunto subscribed my name this 30th day of March, 1914.

FRANCES N. WORKMAN.
